HYDROCARBON ENGINE FUEL PUMP

Lewis H. Haney, Los Angeles, Calif.

Application July 28, 1930, Serial No. 471,167
Renewed April 9, 1935

1 Claim. (Cl. 103—154)

This invention relates to improvements in hydro-carbon engine fuel pumps.

The general object of the invention is to provide an improved means for handling and conditioning the operating fuel of a hydro-carbon engine.

Other objects and the advantages of this invention will be apparent from the following description taken in connection with the accompanying drawings wherein:

Fig. 1 is a view of the injector side of an engine with portions thereof in section and showing my pump;

Fig. 2 is a central section through the engine with my pump also shown in section, and

Fig. 3 is an enlarged fragmentary sectional detail of my fuel pump.

Referring to the drawings by reference characters I have indicated my improved engine generally at 10. As shown this engine comprises a crankcase 12 which includes a lower portion 13 and an upper portion 14, the latter including a pair of spaced cylinders 15 and an enlarged cylinder 16 therebetween. Supported in the crankcase I show a crank shaft 18.

The cylinders 15 are each provided with a head 23 secured to the cylinder block by bolts 24 and each includes a neck 25 which extends downwardly into the cylinder and the outer peripheral wall of which is spaced from the inner surface of the cylinder.

Positioned in each of the cylinders 15 I provide a sleeve valve 26 which is provided in its outer face with a plurality of piston rings 27 and includes a suitable inlet port and an outlet port. This sleeve 26 is adapted to reciprocate in the cylinder and extends into the space between the cylinder wall and neck 25. The lower portion of the neck 25 on its outer surface is provided with a plurality of piston rings 30 which engage the inner surface of the sleeve. Adjacent the lower end of the sleeve 26 is included a tongue 31 which is pivotally connected to a bracket 32 by a pin 33. The bracket may be arranged to be reciprocated by rotation of the shaft 18.

Positioned in each of the sleeves 26 I provide a piston 35 which is suitably connected to the shaft 18. When the crank shaft 18 is rotated the valve sleeve 26 and the pistons 35 reciprocate.

Above the cylinder 16 I provide a housing 53 secured to the engine block by bolts 54. A cover 55 is secured to the housing 53 by bolts 56. Intermediate the cylinder 16 and each of the cylinders 15 and offset from the axis thereof I provide spherical firing chambers indicated at 70. As

shown these chambers are formed by a hemispherical recess 71 provided in the engine block and a similar recess 72 in the body of a fuel pump indicated generally at 73.

In the wall of each of the cylinders 15 I provide a port 75 which communicates with the adjacent firing chamber 70. Furthermore, in the walls of each of the cylinders 15 I provide an exhaust port 76 which is adapted to communicate with the interior of an exhaust manifold 77.

Each of my novel fuel pumps 73 includes a cylinder 80 which is open at its lower end and closed at the upper end where a reduced aperture 81 provided in the top wall communicates with a chamber 82 in an intake manifold 83. In the upper wall of the chamber 82 I provide an aperture 84 which communicates with the interior of the manifold 83 and the passageway through the aperture is controlled by a one-way valve mechanism 85 which may be of any desired construction.

In the wall of the cylinder 80 I provide a port 86 which communicates with the firing chamber 70 and in the body of the fuel pump I provide a by-pass aperture 87 which opens into the cylinder 80 at two vertically aligned spaced points. (See Fig. 1.)

Positioned in each of the cylinders 80 I provide a piston 88 which includes a coaxial bore 89 open at the lower end and closed at the upper end. In the outer surface of the piston 88 I provide a plurality of piston rings 90 and in the side walls of the piston I provide ports 91 and 92.

The piston 88 is adapted to reciprocate in the cylinder 80 and in one position of the piston the port 91 is adapted to register with the port 86 and in another position of the piston the port 92 is adapted to register with the lower opening of the by-pass 87.

Integral with the piston 88 and extending therbelow I provide a tongue 93 which is pivotally connected to a yoke 94 by a pin 95. The yoke 94 is mounted on an eccentric or cam 96 which is secured to a cam shaft 97 supported in bearings 98.

Positioned in the bores 89 of the pistons 88 I provide a plunger 99 which is adapted to reciprocate in the bore and includes an integral downwardly extending tongue 100 which is pivotally connected to a yoke 101 by a pin 102. This yoke 101 is mounted on a cam 103 secured to the cam shaft 97.

The cam shaft 97 is adapted to be rocked through a 90° arc and has secured thereto an arm 55

104 which is pivotally connected as at 105 to the upper end of a vertical rod 106 positioned in a bearing 107 in the crank case. The lower end of the rod 106 is slackly connected as at 5 108 to one end of a lever 109 which is pivotally mounted on a pin 110 supported in bearings 112 on the crank case. Adjacent the end of the lever opposite the rod 106 I provide an elongated aperture 113.

10 Secured to the crank shaft 18 I provide a cam 114 having a collar 115 thereon which is provided with a pin 116 which is positioned in the elongated aperture 113 of the lever 109. Thus when the crank shaft 18 is rotated the cam 114 rotates in the collar 115 raising and lowering it and the pin 116 which in turn rocks the lever 109 thereby reciprocating the rod 106 which in turn rocks the cam shaft 97 through the medium of the arm 104. As the shaft 97 is rocked it reciprocates the pistons 88 through the medium of the cams 96 and the yokes 94 and at the same time it reciprocates the plungers 99 through the medium of the cams 103 and the yokes 101.

15 In the fuel pump body 73 I provide a threaded aperture 118 which communicates with the firing chamber 70 and in which a spark plug 119 is adapted to be positioned.

20 Any desired type of distributing system may be used to direct electrical current to the spark plugs 119 at the proper time and the distributor may be actuated in any desired manner, but in the accompanying drawings I have shown a distributor 120 as adapted to be actuated from the cam shaft 97.

25 A suitable intake manifold 121 communicates with a gasoline carburetor 122 and is provided with a throttle valve 122' and the intake manifold 83 communicates with a fuel oil carburetor 123 and is provided with a throttle valve 124.

30 40 When the engine operates fuel oil will be drawn from the carburetor 123 through the intake manifold 83 to the fuel pumps 73.

45 Fuel is drawn into the upper portion of the cylinder 80 of the fuel pump 73 from the intake manifold 83 through the aperture 81. The fuel is drawn into the cylinder 80 as the piston 88 moves downward and when the piston 88 moves upward the fuel in the cylinder thereabove is compressed until the port 92 in the piston 88 50 registers with the lower opening of the by-pass

87 whereupon the compressed fuel expands into the bore 89 of the piston. As the piston 88 moves downward again and the piston port 92 moves out of register with the lower opening of the by-pass the fuel is trapped in the piston bore 89 between the top of the piston and the top of the plunger 99.

92 10 The piston 88 and the plunger 99 are so timed that the trapped fuel is compressed to the combustion point just previous to the time the piston port 91 registers with the port 86 communicating with the firing chamber 70, so that when the ports 86 and 91 are in register the trapped fuel in the piston 88 passes through these ports.

15 At the time the ports 86 and 91 are fully in register the plunger 99 moves upward and forces all the fuel out of the piston bore 89 and closes the piston port 91 and then the piston 88 again moves upward.

20 From the foregoing description it will be apparent that I have provided an improved hydro-carbon engine fuel pump which is highly efficient and which can be economically manufactured.

25 Having thus described my invention I claim:

30 In a fuel pump, a cylinder having an inlet, a valve for controlling said inlet, said cylinder having an outlet, said cylinder including a pair of spaced openings in communication with each other, a hollow piston in said cylinder, said piston being closed at the portion adjacent to said cylinder inlet, said piston having an outlet port communicating with the interior thereof and adapted in one position of said piston to register 35 with said outlet of said cylinder, a second port in said piston communicating with the interior thereof, said second port in one position of said piston being adapted to register with one of said spaced openings, the other of said openings being near the end of said cylinder, a plunger in said piston adapted to first reduce the volume 40 between the top of said piston and said plunger and when said piston outlet port registers with said outlet port of said cylinder to first allow free 45 passage through said outlet port at the time of compression and then obstruct the passage through said outlet port, and means to move said piston and said plunger.

LEWIS H. HANEY. 50
